[57] CLAIM

The ornamental design for a pendant, as shown and described.

DESCRIPTION

FIG. 1 is a view in perspective of a pendant showing my new design;

FIG. 2 is a view in perspective of the pendant with the switch in alternate position;

FIG. 3 is a front elevational view thereof;

FIG. 4 is a right side elevational view, the left side being a mirror image thereof;

FIG. 5 is a top plan view thereof, the bottom edge being identical; and

FIG. 6 is a rear elevational view thereof.
